UNITED STATES PATENT OFFICE.

LOUIS W. G. FLYNT, OF CHICAGO, ILLINOIS, ASSIGNOR TO UNITED SHOE MACHINERY COMPANY, OF PATERSON, NEW JERSEY, A CORPORATION OF NEW JERSEY.

WHEELING AND EDGE-SETTING MACHINE.

1,080,961.

Specification of Letters Patent.

Patented Dec. 9, 1913.

Application filed February 24, 1913. Serial No. 750,432.

To all whom it may concern:

Be it known that I, LOUIS W. G. FLYNT, a subject of the King of Great Britain, residing at Chicago, in the county of Cook and State of Illinois, have invented certain Improvements in Wheeling and Edge-Setting Machines, of which the following description, in connection with the accompanying drawings, is a specification, like reference characters on the drawings indicating like parts in the several figures.

This invention relates to machines for finishing the marginal portions of the soles of boots and shoes.

More particularly it relates to machines of the type that set the edge of the sole and simultaneously wheel or indent the upper marginal surface of the sole.

The invention aims to devise a machine of the character indicated which shall have provision for effecting readily the adjustment of the tools and for holding them securely in their adjusted positions, and particularly to devise a construction that can be manufactured more economically than similar machines heretofore proposed.

The several features of the invention will be clearly understood from the following description of a preferred embodiment thereof, reference being made to the accompanying drawings, in which—

Figure 1 is a view in side elevation of the head of a machine for simultaneously setting and wheeling the marginal portions of shoe soles; Fig. 2 is a longitudinal sectional view of the supporting and adjusting mechanism for the tools; and Fig. 3 is a front elevation of the mechanism shown in Fig. 1.

In the drawings, 2 indicates a portion of the machine frame having suitable bearings for the support of a rock shaft 4 that is caused to oscillate rapidly about its axis by any suitable mechanism. As shown, this shaft is provided at its forward end with a depending portion 6 which oscillates with the shaft and will be referred to hereinafter as the rocker frame.

A tool carrier 8 of substantially U-shape in transverse cross section is pivotally connected at 10 to the rear end of the rocker frame and receives the forward part of the rocker frame between its vertical walls, these overlapping walls being slotted to receive a bolt 12 that extends transversely through the rocker frame. By this construction the tool

carrier 8 is enabled to have a limited pivotal movement on the rocker frame; and in order to make this movement yielding a spiral spring 14 is located in a bore or seat formed in the lower side of the frame and bears against the bottom wall of the tool carrier. This carrier may, if desired, be formed by stamping out a piece of heavy sheet metal of suitable form and bending it up into the shape shown, the apertures for the pivots and bolts being formed in the stamping operation.

The tool carrier supports an indenting wheel 16 and an edge setting tool 18, the acting faces of these tools being so located that they can operate simultaneously on the marginal portion of a shoe sole, as indicated in Fig. 1. The supporting member for the edge setting tool preferably consists of a cylindrical rod 20 mounted beneath the rocker frame 8 in the eye of a draw bar 22 and a guide 24 secured to the tool carrier. This rod is free to slide through its supporting members toward or from the indenting wheel 16 and is urged toward the wheel by means of a spring 26 encircling the rod and bearing at one end against the stationary guide 24 and at its opposite end against a pin 28 projecting transversely through the rod 20. Another transverse pin 30 carried by the rod near its rearward end is adapted to engage the guide 24 to limit the forward movement of the rod under the influence of the spring 26.

The edge setting tool shown is formed from bar stock of rectangular cross section and has a socket drilled in its shank to receive the end of the rod 20 so that when the tool is in operative position one of its flat faces bears against the lower side of the tool carrier 8. In order to clamp the tool in the tool carrier, the stem of the draw bar 22 is provided with a nut 32 which is arranged to slide in a bore formed in the rocker frame 6 concentrically with the seat for the spring 14 and a spiral spring 34 is positioned in this bore inside the spring 14 and bears at one end against the bottom of the tool carrier and at its opposite end against the nut 32. The tension of the spring 34 is transmitted through the draw bolt to the tool supporting member 20 and clamps the flat surface of the edge setting tool against the under side of the tool carrier and also locks the rod 20 against movement. If desired,

the surface of the rod 20 may be roughened or threaded as indicated in Fig. 1, and the eye of the draw bolt may be correspondingly roughened or threaded to insure a more positive locking of the rod in adjusted position.

The support for the indenting wheel 16 comprises a casing 36 mounted between the walls of the tool carrier 8 on a pivot bolt 38 so that it can be moved into different angular positions with relation to the edge setting tool 18. Within the casing a slide 40 is mounted for movement toward and from the edge setting tool and a spindle 42, upon which the indenting wheel is rotatably mounted, is removably supported in the slide by means of a draw bolt 44 having an eye to receive the spindle and an internally threaded shank to receive a clamping screw 46. The bolt 44 slides in a bore formed in the member 40 and the head of the screw 46 bears on the bottom of an enlarged portion of said bore, as shown in Fig. 2. The slide 40 is urged out of the casing 36 by means of a spiral spring 48 positioned in the casing behind the slide but this movement is limited by an adjustable stop rod 50 having a hooked end arranged to engage the forward end of the slide, the shank of the rod being adjustable in a longitudinal aperture extending through a boss on the top of the casing. A draw bolt 52 engages the rod and is operated by a nut 54 threaded on to its stem to clamp the rod in adjusted position.

The heating of the tools 16 and 18 is effected by small gas burners 56 and 58, respectively, having connection with a gas supply pipe 60 that is firmly secured to the frame. This pipe also serves as a support for an adjustable block 62 in which a finger hook 64 is mounted to slide toward and from position to be engaged readily by the workman when operating around the toe portion of a shoe.

From the foregoing description it will be evident that in order to remove or adjust the edge setting iron 18 it is merely necessary to depress the draw bolt 22, thus releasing the rod 20 and unclamping the tool 18. The tool may then be removed and another substituted for it, the proper adjustment of the new tool being effected by pushing it back against the tension of the spring 34 until it has arrived in the desired position, when the pressure on the draw bolt should be released, allowing the spring 34 to clamp the rod 20 and the tool in adjusted position on the carrier. For the purpose of further facilitating the adjustment or removal of the tools, the end of the shaft 4 may be drilled, as best indicated at 66, Fig. 3, to receive a stud projecting from one side of a tool of the form indicated in dotted lines in Fig. 3, this tool having a cam

portion adapted to bear on the nut 32 to depress the draw bar 22 when turned to the left, as viewed in said figure. Angular adjustment of the indenting wheel 16 with relation to the edge setting tool 18 is effected merely by tipping the casing 36 until the wheel comes into the desired angular position, the friction between the walls of the tool carrier and the sides of the casing being sufficient to hold the casing in adjusted position.

The adjustment of the indenting wheel transversely of the acting face of the edge setting tool is, of course, effected by loosening the stop rod 50 and moving it forward or back until it holds the slide in a position that brings the wheel into the desired relationship to the edge setting tool. When it is desired to remove the indenting wheel, the stop rod 50 is turned sufficiently to release the slide from contact therewith and allow it to be pushed forwardly by the spring 48. The clamping screw 46 may then be loosened to release the spindle 42 from the clamping action of the draw bolt 44, whereupon the spindle may be removed from the slide taking the indenting wheel with it.

Having thus described the invention, what is claimed as new and desired to be secured by Letters Patent of the United States is:

1. In a machine of the class described the combination of a rocker frame, a tool carrier mounted to rock with said frame, a tool supporting member carried by said tool carrier and mounted for movement relatively to said carrier, and a draw bolt arranged to engage said member to lock the member and tool in operative position on the carrier.

2. In a machine of the class described the combination of a rocker frame, a tool carrier mounted to rock with said frame, a tool supporting member carried by said tool carrier and mounted for adjustment relatively to said carrier, a spring tending to move said member relatively to the carrier, and a draw bolt arranged to engage said member to lock it in adjusted position.

3. In a machine of the class described the combination of a rocker frame, a tool carrier mounted to rock with said frame, a tool supporting rod mounted at one side of said carrier, an edge setting tool having a flat surface to engage the side of the carrier and having a socket to receive said rod, and means arranged to act upon said rod to clamp the flat surface of the tool against the side of the tool carrier.

4. In a machine of the class described the combination of a rocker frame, a tool carrier mounted for limited pivotal movement on said frame, a spring interposed between said frame and carrier, an indenting wheel supported by said tool carrier, a tool supporting rod mounted on said carrier for

movement toward and from said indenting wheel, a spring acting on said rod to move it toward said wheel, an edge setting tool mounted on said rod with its acting face positioned adjacent to said wheel, a draw bolt engaging said rod, and a spring acting on said draw bolt to clamp said rod and tool in adjusted position on the carrier.

5. In a machine of the class described, the combination of a rocker frame, a tool carrier mounted to rock with said frame, an edge setting tool supported by said carrier, a casing supported on said carrier for angular adjustment relatively to said tool, a 10 slide mounted in said casing for movement toward and from the tool, a spindle removably supported in said slide, an indenting wheel mounted on said spindle adjacent to said edge setting tool, and a draw bolt carried by the slide and arranged to engage said spindle to lock it in adjusted position in the slide.

6. In a machine of the class described the combination of a rocker frame, a tool carrier pivoted to said rocker frame and having side walls arranged to overlap a portion of said frame, a spring interposed between said frame and carrier and tending to force the carrier away from the frame, 25 means for limiting the movement of the carrier under the influence of said spring, an edge setting tool mounted on said carrier, a casing supported between said side walls of the carrier for angular adjustment with relation to said edge setting tool and an indenting wheel mounted in said casing for adjustment toward and from said tool.

7. In a machine of the class described the combination of a rocker frame, a tool car-

rier mounted to rock with said frame, an edge setting tool mounted on said carrier, a casing supported on said carrier for angular adjustment relatively to said tool, a slide mounted in said casing for movement toward and from the tool, an indenting wheel removably secured to said slide, a stationary stop adjustably supported in the casing and arranged to limit the forward movement of the slide, and means for holding said stop in adjusted position.

8. In a machine of the class described the combination of a rocker frame, a tool carrier pivoted to said rocker frame and having side walls arranged to overlap a portion of said frame, means for limiting the pivotal movement of said carrier on said rocker frame, a spiral spring seated in said frame and bearing on said carrier, an indenting wheel mounted on said carrier, a tool supporting rod mounted at one side of said carrier for adjustment toward and from said indenting wheel, an edge setting tool positioned on said rod and having a flat surface to bear against a face of the carrier, a draw bolt embracing said rod and having a stem extending through said spiral spring, a second spring positioned within the first mentioned spring and arranged to act on said bolt to clamp the rod and tool in adjusted position on the carrier.

In testimony whereof I have signed my name to this specification in the presence of two subscribing witnesses.

LOUIS W. G. FLYNT.
